ELECTROMECHANICAL ARTICLE STORAGE AND RETRIEVAL UNIT

John L. Gianfagna, Marietta, Ohio, assignor to Sperry
Rand Corporation, New York, N.Y.

Filed Oct. 30, 1970, Ser. No. 25,750

Term of patent 14 years

Int. Cl. D6—04

U.S. Cl. D6—189

FIG. 1.

FIG. 2.

FIG. 3.

FIG. 4.

FIG. 1 is a front perspective view of an electromechanical article storage and retrieval unit showing my new design;

FIG. 2 is a front elevational view thereof;

FIG. 3 is a side elevational view thereof; and

FIG. 4 is a front perspective view of a second embodiment of new design for an electromechanical article storage and retrieval unit.

The back of the unit is plain and unornamented.

I claim:

The ornamental design for an electromechanical article storage and retrieval unit, substantially as shown and described.
